Atty's:

UNITED STATES PATENT OFFICE.

ELMER S. SHIMER, OF MILTON, PENNSYLVANIA, ASSIGNOR TO SAMUEL J. SHIMER & SONS, OF MILTON, PENNSYLVANIA, A CORPORATION OF PENNSYLVANIA.

ROTARY CUTTER-HEAD.

1,190,197.

Specification of Letters Patent.

Patented July 4, 1916.

Application filed July 27, 1915. Serial No. 42,184.

To all whom it may concern:

Be it known that I, ELMER S. SHIMER, a citizen of the United States, residing at Milton, in the county of Northumberland and State of Pennsylvania, have invented certain new and useful Improvements in Rotary Cutter-Heads, of which the following is a specification.

My invention relates to an improvement 10 in rotary cutter-heads for wood-working machines, and the present invention is more especially designed for jointing the edge of the plank, it being an improvement on the construction disclosed in Letters Patent No. 15 874,871, granted to me on December 24, 1907, the present invention, however, differing from the patented construction in the structure of the knife or bit-holder, which in the present instance is in two parts instead of 20 one, the lower edges of which overlap or interlock at the inner end of the recess or seat in the head, which the bit-holder fits; and in the interlocking corrugations in the contiguous faces of the bit and cutter and 25 one section of the bit-holder.

In the accompanying drawings:—Figure 1 is an end view of the cutter-head; Fig. 2 is a face view of one of the bits or cutters showing the corrugations; and Figs. 3 and 30 4 are views of the two sections of the bit-holder.

The cutter-head 1 is provided with several recesses 2, 2, three being shown in the present instance, although there might obviously be 35 even more or less. These grooves preferably have parallel walls and are deepened at one portion, as at 3, and this deepened portion is provided with a transverse channel or groove 4.

40 The bit or cutter 5 is provided on one face with corrugations 6, which fit and interlock with corresponding corrugations 7 on the section 8 of the bit-holder, which latter has a longitudinal rib 9 which fits the channel 45 to gage the position of section 8 of the bit-holder and hold it in place. The other sec-

tion 10 of the bit-holder is L-shaped to fit the recess 3, and reach under and engage the inner end of section 8 of the bit-holder, it not only fitting the recess 3 but embracing 50 the inner face of the knife or cutter 5, as shown clearly in Fig. 1. The screws of the bolt 11 fit corresponding threads in section 10, and when its head is screwed back against the solid rear wall of recess 2, the parts are 55 rigidly clamped in place, as is well understood.

It is the knives or cutters 5 that wear down. They are set at a distance equal to one of the corrugations, the sections 8 and 60 10 of the bit-holder being separated for the purpose, after which they are put together with the inner ends of the two sections 8 and 10 interlocking with each other, as shown in Fig. 1, after which the bolts (two 65 of which are usually employed) are screwed or thrown back against the rear wall of the recess 2, and the bit or knife and its holder are held firmly in place.

I claim:

70 The combination of a cutter head having a recessed periphery, the recess having a transverse groove on one side wall thereof, a bit, a bit holder, comprising two sections which embrace the bit between them, one 75 section having a longitudinal rib on one side adapted to fit the groove in the wall of the recess and one end of the other section of the bit holder substantially filling the space between the inner end of the recess and the 80 inner end of the other section and a screw which turns in a threaded hole in one section and is adapted to be backed up against a wall of the recess, whereby the cutter is rigidly held by the parts of the bit holder 85 and the walls of the recess.

In testimony whereof I affix my signature, in the presence of two witnesses.

ELMER S. SHIMER.

Witnesses:

SAMUEL J. SHIMER,
JAMES B. KRAUSER.
